UNITED STATES PATENT OFFICE.

SAMUEL A. JONES, OF DESHLER, OHIO.

MAIL-BOX.

SPECIFICATION forming part of Letters Patent No. 731,372, dated June 16, 1903.

Application filed December 23, 1902. Serial No. 136,379. (No model.)

To all whom it may concern:

Be it known that I, SAMUEL A. JONES, a citizen of the United States, residing at Deshler, in the county of Henry and State of Ohio, have invented a new and useful Mail-Box, of which the following is a specification.

The present invention relates to that class of mail-boxes used in the rural mail delivery system in this country, and more especially to those which include in their make-up a stationary cover member, beneath which is journaled a receptacle member having an entrance-opening in its walls, which is arranged to be placed beneath, and thus closed 15 by the cover member.

It is the object of the present invention to provide a very simple though effective signal for this class of boxes, which may be easily placed in operative position by the depositor of mail and will be securely locked in such position when the box is closed, being released, however, and automatically dropping to inoperative and unexposed position upon the opening of the box by the collector, thus causing him no delay by overcoming the necessity for his separately moving said signal.

The preferred embodiment of the invention is illustrated in the accompanying drawings, wherein—

Figure 1 is a perspective view of the improved box, showing the signal in its operative position. Fig. 2 is an end elevation of the same with the box open, and the signal in inoperative position. Fig. 3 is a vertical sectional view through the end of the box carrying the signal.

Similar reference-numerals indicate corresponding parts in all the figures of the drawings.

In the present embodiment the box proper is made up of two members—a cover 10 and a receptacle 11—both of which are preferably constructed of sheet metal.

The cover member 10 consists of a roof formed of oppositely-sloping sides 12, having at their lower edges outturned beads 13, forming eaves-troughs. Secured beneath and to the ends of the roof are gables 14, having 45 outstanding flanges 15, fastened by rivets 16 to the roof. The cover is supported by a bracket comprising upstanding arms 17, riv-

eted to the gables at their upper ends and having their lower ends connected by a horizontal bar 18, provided with an intermediate 55 twisted portion 19, which is adapted to be placed flat against a suitable post 20 and bolted thereto in the manner shown.

The receptacle member 11 is substantially cylindrical in form, comprising end caps 21, 60 to which is suitably fastened an annular wall 22, the ends of this wall being spaced apart to provide a suitable entrance-opening and having outturned beads 23. This receptacle member is journaled beneath the cover 65 member, and to this end trunnions 24 are fastened in the upright arms 17, the caps 21 being revolvable upon these trunnions. It will thus be apparent that the receptacle member may be revolved, so that the entrance-opening will be closed by the cover member 10 and the interior of the box thus completely inclosed against the ingress of moisture, or by rotating the receptacle member in an opposite direction it may be opened 75 for the insertion or removal of mail, a suitable handle 25 being provided for conveniently operating the member.

Pivoted between its ends to the end of the cover 10 is a signal-arm 26, the outer end of 80 which is provided with a signal 27, preferably, though not necessarily, in the form of a disk and colored, so that it may be readily seen. It will be noted that the pivot 28 of the arm is located above the pivot-axis of the 85 receptacle member, so that when the signal 27 is elevated it will be exposed at one side of the mail-box and when dropped it will be in line therewith, as shown in Fig. 2. The signal is held in its elevated position by a supporting device mounted upon the adjacent end of the receptacle member and carried by a portion of the locking means for the box. This means includes a projecting tongue 29, secured to the end of the cover member, and 90 a substantially U-shaped clip 30, fastened to the end of the receptacle member, the outer terminal 31 of this clip constituting a tongue which coacts with the tongue 29 when the receptacle member is in closed position, said 95 tongues having openings 32 therein arranged to receive a suitable padlock, as indicated in Fig. 1. The inner terminal 33 of the clip constitutes a projecting lug which is so arranged 100

that it may be placed over the inner end of the signal-arm, and thus support the signal in its elevated position as long as the mail-box is closed. In the preferred construction 5 the outer end 34 of the adjacent trunnion 24 projects beyond the arm 17 and is located in the path of movement of the inner end of the signal-arm 26, and therefore the lug 33 and the projecting end 34 of the journal constitute 10 keepers between which the signal-arm may be secured. As long as there is no mail deposited in the box for collection, the signal is in its inoperative position, as shown in Fig. 2, in which case it being in line with the box 15 is not prominently displayed. After mail has been placed in the box for collection the depositor as he closes said box first elevates the signal to the position shown in Fig. 1, and thus when the box is locked said signal will 20 be secured in operative position, notifying the collector of the presence of mail. In removing this mail the collector must necessarily rotate the receptacle member to its open position, whereupon the lug 33 will be 25 moved away from the lower end of the signal-arm and the signal will automatically drop to its inoperative position. Said lug, furthermore, constitutes a stop that strikes the adjacent arm 17 of the bracket, and thus limits 30 the range of movement of the receptacle in one direction, the U-shaped bracket also striking against the edge of the gable in closing the receptacle, thereby properly alining the tongues 29 and 31. It will be apparent 35 that this structure is very simple in its make-up, though it is entirely efficient, as it does not delay the collector, and, furthermore, the signal is securely fastened in its operative position against accidental movement to an 40 inoperative station.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 45 of the invention.

Having thus fully described my invention, what I claim as new, and desire to secure by Letters Patent, is—

1. In a mail-box, the combination with a 55 stationary cover member, of a rotatable receptacle member journaled beneath the cover member, a signal pivoted to the cover member, and holding means carried by the receptacle and arranged to engage the signal to hold the same elevated when the receptacle member is closed, said means being movable out of engagement with the signal when the receptacle member is rotated to open position, to permit the dropping of said signal.

2. In a mail-box, the combination with a 65 stationary cover member, of a rotatable receptacle member journaled beneath the cover

member, a signal pivoted above the journal-axis of the receptacle member and arranged to swing downwardly into line with the end of the same, and holding means carried by the receptacle member and arranged to engage the signal to hold the same elevated when the receptacle is closed, said means being movable out of engagement with the signal to release the same when the receptacle member is rotated to open position.

3. In a mail-box, the combination with a stationary cover member, of a rotatable receptacle member journaled beneath the cover member, a signal-arm pivoted between its ends at one end of the cover member and carrying a signal at its outer end, and holding means carried by the receptacle member and arranged to engage the inner end of the arm to hold the signal in a predetermined exposed position when the receptacle is closed, said means disengaging the signal to permit the same to drop when the receptacle is rotated to open position.

4. In a mail-box, the combination with a cover member, of a signal-arm pivoted at one end of the cover member, said arm carrying a signal at its outer end that can be arranged in elevated position, a rotatable receptacle 95 member journaled beneath the cover member, and a lug projecting from the end of the receptacle member and constituting a support that engages the inner end of the arm to hold the signal in elevated position.

5. In a mail-box, the combination with a cover member, of a signal-arm pivoted at one end of the cover member, said arm carrying a signal at its outer end that can be arranged in elevated position, a rotatable receptacle 105 member journaled beneath the cover member, and a lug projecting from the end of the receptacle member and constituting a support that engages the inner end of the arm to hold the signal in elevated position, said lug being movable away from the inner end of the arm upon the rotation of the receptacle member to open position.

6. In a mail-box, the combination with a cover member and a receptacle member, of a 115 signal movably mounted on the box and arranged to be placed in a predetermined exposed position, and locking means for the cover and receptacle members, said locking means including a support for the signal 120 which automatically disengages therefrom when the box is opened to release said signal.

7. In a mail-box, the combination with a cover member and a receptacle member, of a 125 movable signal arranged to be placed in a predetermined exposed position, and locking means for the cover and receptacle members, said means carrying a lug that engages the signal to support the same and is detachable therefrom when the box is opened to release 130 said signal.

8. In a mail-box, the combination with a cover member having a locking-tongue, of a receptacle member, a movable signal arranged

to be placed in a predetermined exposed position, and a U-shaped clip secured to the receptacle member, one end of the clip constituting a locking-tongue that coacts with 5 the tongue of the cover member, the other end forming a projecting lug that engages the signal to support the same.

9. In a mail-box, the combination with a cover member, of a receptacle member journaled beneath the same and having a projecting trunnion; a signal-arm pivoted at the end of the cover member, and a lug carried by the receptacle member, said lug and trunnion constituting keepers between which the 15 signal-arm may be secured when the receptacle is in closed position.

10. In a mail-box, the combination with relatively movable receptacle and cover members, of a movable signal, and means carried by one of the members for holding the signal 20 in a predetermined position, said means automatically disengaging from the signal and also constituting a stop to limit the movement of the member when the box is opened.

In testimony that I claim the foregoing as 25 my own I have hereto affixed my signature in the presence of two witnesses.

SAMUEL A. JONES.
